UNITED STATES PATENT OFFICE

ROBERT WLADISLAS DE MONTALK, OF WELLINGTON, NEW ZEALAND

SHOCK ABSORBING OR MINIMIZING MEANS FOR BUILDINGS

Application filed June 10, 1930, Serial No. 460,553, and in New Zealand July 11, 1929.

This invention relates to means used for absorbing or minimizing shock to buildings arising from earthquakes, vibrations caused by heavy traffic, or other disturbances of the earth's surface.

The invention comprises means whereby a bed, which I call a severer, is placed and retained between the base of a building and its solid foundation, the severer being composed of material which will absorb or minimize shocks, thereby saving the building therefrom.

In the accompanying drawings in conjunction with which the invention will be described,

Figs. 1, 2 and 3 are part vertical sectional elevations illustrating different forms of the invention.

In carrying out the invention, a platform 1 constructed of reinforced concrete is laid down to cover the whole area whereon the building 2 is to be constructed, and on the platform is spread the severer 3 consisting of a layer of loose material such as shingle, sand, earth or the like, and upon this severer the building 2 is erected with a sole plate 2a approximately of the same area as the platform.

The platform 1 is laid upon any ordinary foundation 4 such as solid ground, piles or other formation or structure.

The platform 1 is provided with a rim 1a around its periphery for retaining the severer 3, which has a depth equal to the depth of the rim 1a, and is screeded off to make a level surface.

The severer 3 is covered over with building paper 5 or the like which will prevent concrete when being laid from adhering to the severer.

The building 2 is constructed preferably of reinforced concrete and having its walls integral with the sole plate 2a, the walls and sole plate thus forming a unit. The platform 1 is made with the interior of its rim 1a somewhat larger than the building 2, so that a space is left all round between the building and the rim.

Drainage holes 6 are made from the sur-

face of the platform 1 to the exterior to allow water to escape from the severer.

The sole plate 2a constructed of reinforced concrete is laid on the building paper 5 covering the severer 3, and this sole plate may 55 form the floor of the bottom storey.

Where it is necessary to step the foundations 4 from one level to another in order to conform to the configuration of the ground, walls 7 are constructed to form a continuation of the sole plate 2a from one level to the next, with a space 8 between said walls 7 and the walls 1a of the platform. At each higher level a rim 7a is formed to prevent the severer 3 falling into the space 8 between the walls, the adjacent parts of the sole plate 2a being recessed at 9 over the rims 7a.

Where it is required to construct the building 2 adjacent to an existing building so that there will not be a space between the buildings, a projecting rim 1a is not possible, but instead the wall of the building 2 is formed with a rebate 10 so that it sits over the rim 1a (Fig. 2), said rebate 10 being spaced away from the top and inside of the rim 1a. In order to form this rebate, a layer of sand or the like which will form a parting, is laid upon the surface of the rim 1a, the parting being held on the outside by the adjacent building, and on the inner side by thin sheet 70 metal, wood strips, or the like, which are afterwards removed. This parting is removed later through holes 11 leading from the surface of the sole plate to the rebate. A

vacuum exhaust is applied to the holes 11 after the concrete walls have set and the parting thereby drawn out. Where it is desired to make the wall sit over the rim 1a as just described, but there is no adjacent building, strips of sheet iron, wood or the like are placed on the outside of the rim 1a as well as inside for the purpose of retaining the parting, in which case the parting may be any suitable material which can be readily removed.

When desired, other materials may be used for the severer, such as building paper alone, or layers of building paper with a layer of asphalt between. Instead of building paper, other known materials may be used for pre-

venting the concrete from adhering to the severer.

The foundation as above described, forms a damp course over the whole area of the base of the building, and spreads the weight of the building over the whole area, and does not exceed the cost in many cases of foundations and ground or basement floor.

What I do claim and desire to obtain by Letters Patent of the United States of America is:—

1. Means for the purpose set forth, comprising a platform laid upon a foundation and integrally formed with an upwardly projecting rim; a layer of loose material on said platform and retained by the rim thereof to form a bed for a building between which and said rim a space is provided, and the rim at the juncture with the base being provided with drainage openings inclined downwardly from the upper surface of the base.
2. Means for the purpose set forth, as in claim 1, wherein the base of the building is rebated to sit over the rim, a space being provided between the latter and the building.
3. Means for the purpose set forth as in claim 1, wherein the platform is stepped and the base of the building is shaped to sit on layers of loose material on the steps, spaces being provided between the portions of the platform and base connecting the steps.
4. Means for the purpose set forth, as in claim 1, wherein the platform is stepped and has a rim at the outer edge of each step, the base of the building being shaped to sit on layers of loose material on the steps and over the rims of the latter, spaces being provided between the portions of the platform and base connecting the steps.

In testimony whereof I have signed my name to this specification.

ROBERT WLADISLAS de MONTALK.
